CORNICE FOR WINDOW CURTAINS

Cosimo D. Bruno, Youngstown, Ohio

Application April 28, 1950, Serial No. 158,711

5 Claims. (Cl. 160—19)

1

My invention relates to improvements in window curtain cornices.

A primary object of my invention is to provide an ornamental cornice which is readily detachably mounted upon a curtain rod secured to a window frame.

A further object is to provide an ornamental cornice which will completely cover and conceal the curtain rod carrying it, as well as the top of the wooden window frame.

A further object is to provide a cornice of the above-mentioned character which is highly simplified in construction, compact, sturdy and durable and neat and attractive in appearance.

A still further object is to provide an ornamental cornice which may be formed in separate, detachable, prefabricated sections, the sections having simplified and novel attaching means for forming close-fitting and neat joints between the sections.

A further object is to provide a window curtain cornice which embodies no screws or nails which must be driven into the woodwork or window frame, thus damaging it.

A still further object of the invention is to provide a cornice of the above-mentioned character which may be assembled to fit various standard sizes of window frames, and which is constructed so as to be quite inexpensive to manufacture.

Other objects and advantages of the invention will be apparent during the course of the following description.

In the accompanying drawings forming a part of this application, and in which like numerals are employed to designate like parts throughout the same:

Figure 1 is a front perspective view of a window curtain cornice embodying my invention;

Figure 2 is a plan view of the cornice, parts being broken away;

Figure 3 is an enlarged, fragmentary, horizontal, sectional view taken on line 3—3 of Figure 1;

Figure 4 is an enlarged, transverse, vertical, sectional view taken on line 4—4 of Figure 2;

Figure 5 is an enlarged, fragmentary, exploded, perspective view showing a vertical joint between two adjacent cornice sections of the cornice illustrated in Figure 1;

Figure 6 is a fragmentary, side elevational view of a modified form of joint between two adjacent cornice sections;

Figure 7 is an enlarged, fragmentary, horizontal sectional view taken on line 7—7 of Figure 6;

Figure 8 is an enlarged, fragmentary vertical, sectional view taken on line 8—8 of Figure 6;

2

Figure 9 is a fragmentary, exploded, perspective view of a pair of adjacent cornice sections and showing a further modified form of joint between such sections;

Figure 10 is an enlarged, fragmentary, horizontal, sectional view through the joint illustrated in Figure 9;

Figure 11 is a fragmentary, perspective view of adjacent cornice sections having a still further modified form of joint; and

Figure 12 is an enlarged, fragmentary, horizontal, sectional view taken on line 12—12 of Figure 11.

In the drawings, where, for the purpose of illustration, are shown preferred embodiments of my invention, attention is directed first to Figures 1 to 5, inclusive, wherein the numeral 15 designates the usual rectangular wooden window frame at the inner side of a window 16, and including a top horizontal frame side or member 17, and vertical frame sides 18.

Conventional horizontal curtain rod support brackets 19 are suitably rigidly secured to the top window frame member 17 near its opposite ends, 25 and a conventional, telescopic, adjustable curtain rod 20 is detachably mounted upon the support brackets 19 in the usual manner. The curtain rod 20 comprises the usual tubular, telescopic rod sections 21 and 22 which are disposed laterally forwardly of the top frame member 17 and parallel thereto. The rod sections 21 and 22 have transverse extensions or arms 23 at their opposite ends, and these arms 23 are directed inwardly for engagement upon the support brackets 19.

As best shown in Figure 4, the telescopic curtain rod sections 21 and 22 are somewhat flattened vertically, as are the transverse extensions or arms 23.

My improved ornamental cornice is designated generally by the numeral 24, and the cornice is bodily detachably mounted upon the curtain rod 26, as will be more fully described. The cornice 24 comprises L-shaped corner or end sections 25 and a front or central section 26 arranged

between the corner sections 25 and detachably secured thereto. The front cornice section 26 comprises a substantially flat, vertical plate or panel 27, which may have its bottom end fluted, as at 28, for the purpose of ornamentation. The top, horizontal edge 29 of the front section 26 is straight and disposed substantially adjacent to the top edge of the top window frame member 17, Figure 4. The plate 27 is provided at its opposite ends with inturned or rearwardly

extending, spaced, vertical, apertured extensions

or ears 30 integral therewith, and the plate 27 is provided between the vertically spaced ears 30 with end longitudinal extensions or tabs 31. In assembly, the tabs 31 overlap and lie adjacent to the inner faces of the forward plates or panels 32 of the end or corner cornice sections 25. The panels 32 are provided adjacent to their free vertical edges with integral, inturned or rearwardly extending, apertured extensions or ears 33, which are vertically spaced for receiving the tabs 31 between them. The apertured ears 33 are disposed in a vertical plane and adapted to register in assembly with the ears 30 of the front or center cornice section 26. The openings or apertures of the companion ears 30 and 33 register in assembly for the reception of bolts 34 detachably securing the center and corner cornice sections 26 and 25 together. As viewed from the front in assembly, Figure 1, the plates or panels 27 and 32 constitute a substantially continuous, flat, depending, vertical panel completely concealing the top frame member 17, curtain rod 20, bolts 34 and associated elements from view. The end or corner cornice sections 25 further comprise transverse or end vertical panels 35, integral with the panels 32 and disposed at right angles thereto. The end panels 35 extend inwardly and have their rear free edges 36 arranged adjacent to the outer vertical edges of the frame sides 18, Figure 1.

The top edges of the end panels 35 are horizontally disposed and straight, and arranged at the same elevation as the top edge 29 of the front panel 27. A continuous ornamental molding or bead 37, which is substantially inverted U-shaped, Figure 4, is applied to the top edges of the panels 27, 32 and 35, and the molding 37 extends entirely about the top of the cornice 24, as shown in Figure 1. If desired, the ornamental bead or molding 37 may be constructed in telescopic, adjustable sections like the curtain rod 20.

Spot welded or otherwise permanently rigidly secured to the inner faces of the vertical panels 27, 32 and 35 are a plurality of laterally inwardly offset mounting brackets or hangers 38, all of which are disposed at the same elevation and spaced below the top edges of the panels 27, 32 and 35 for a substantial distance, Figure 4. The hangers 38 include top horizontal webs or shoulders 39 for engagement upon the top of the curtain rod 20, and inner depending, vertical legs or webs 40 which engage the inner, vertical, flattened sides of the curtain rod, as shown. As best shown in Figure 2, the front panel 27 is preferably equipped with a longitudinally spaced pair of the hangers 38, while the panels 32 and 35 are preferably equipped with a single hanger 39. However, any desired number of the hangers 38 may be provided for readily detachably supporting the cornice 24 on the curtain rod 20. Likewise, while I have shown a single forward cornice section 26, I also contemplate using any desired number of the sections 26 arranged in end-to-end relation and connected with the inner sections 25 in exactly the same manner described above, in order to accommodate window frames of various widths.

Near and above the hangers 38, and likewise permanently rigidly secured to the inner faces of the vertical panels 27, 32 and 35 are a plurality of inwardly projecting support lugs or stops 41, all arranged at the same elevation and spaced below the top edge of the cornice 24 a substantial distance, Figure 4. The front panel 27 is preferably provided at its longitudinal

center with one of the lugs 41, and the end panels 35 are likewise preferably equipped near their ends adjacent to the window frame 15 with one of the lugs 41, Figure 2. The forward panels 32 are provided adjacent to the corners of the cornice 24 with a lug 41, and it should be understood that any desired number of the lugs or stops 41 may be employed.

A flat, horizontal, removable dust cover or plate 42 rests upon the lugs or stops 41, and is likewise disposed below the top edge of the cornice 24, Figure 4. The cover plate 42 aids greatly in preventing dust from collecting on the curtains suspended from the rod 20, not shown.

It is thus seen that my entire cornice assembly 24 is bodily detachably mounted upon the curtain rod 20, so that it may be removed therefrom when desired. The cornice sections, molding 37 and cover plate 42 may be formed of light gauge sheet metal, some suitable plastics material, or any other suitable thin sheet material which possesses sufficient rigidity and strength.

Attention is directed next to Figures 6 to 8, inclusive, wherein a modified type of joint between one corner section 25' of the cornice and its front section 26' is illustrated. In this form of the invention, the front panels 27' and 32' have adjacent, free, laterally spaced, vertical edges 43, detachably secured in place in assembly by means of an elongated, vertical locking slide or clip 44. The locking slide 44 is formed from a unitary section of resilient sheet metal, or the like, and comprises a pair of inner or rear, flat, vertical, elongated flanges or tongues 45 which lie against the inner surfaces of the vertical panels 27' and 32' in assembly. The tongues 45 are bent at their inner ends for forming integral, separate, opposed, U-shaped portions or loops 46 arranged in substantially contacting relation, as shown, and forward, flat, vertical flanges or tongues 47 are integrally secured to the U-shaped portions 46 and lie adjacent to the outer faces of the panels 27' and 32', Figure 10. The tongues 47 of the slide or clip 44 are integrally secured together by means of a forward, flat, vertical web or plate 48. As shown clearly in Figure 6, the slide or clip 44 extends throughout the major portion of the height of the panels 27' and 32', and the clip 44 is provided at its top with a short, horizontal, laterally inwardly projecting tab or stop 49, which engages the top edge 29' of the panel 27' to limit the downward movement of the slide or clip 44. The slide or clip 44 is applied to and removed from the cornice sections which it connects from the tops of such sections, and it should, of course, be understood that one of the clips 44 is provided between each adjacent pair of corner and front cornice sections, and between each adjacent pair of front cornice sections, if more than one front section is employed. All other parts of the cornice illustrated in Figures 6 to 8 are identical with corresponding parts shown and described in connection with the first form of the invention. In Figures 6 to 8, the ornamental molding 37 has been omitted from the drawings for the purpose of clarity, and it should be understood that the molding is applied to the top of the cornice in the manner shown and described in connection with the first form of the invention.

In Figures 9 and 10, I have shown a further modified form of joint between adjacent corner and front cornice sections 50 and 51. In this form of the invention, the adjacent ends of the front, vertical panels 52 and 53 overlap, as shown, and the panels 52 and 53 are provided at their

free vertical edges with interlocking, elongated, vertical, U-shaped extensions or tongues 54 which frictionally interfit in assembly, as shown in Figure 10. In this form of the invention, no separate fastening elements are needed for detachably securing adjacent cornice sections together, since the friction between the interfitting extensions 54 is sufficient to detachably secure the cornice sections together in assembly. All other parts of the cornice illustrated in Figures 9 and 10 are identical with corresponding parts shown and described in connection with the first form of the invention.

In Figures 11 and 12, I have shown a still further modified form of joint between adjacent corner and front cornice sections 55 and 56. In this form of the invention, the front panel 57 of the corner cornice section 55 has its straight, vertical edge 58 freely disposed for frictional engagement within an elongated, vertical, U-shaped flange, or locking element, 59 integrally secured to the adjacent, vertical edge of the panel 60 of the cornice section 56. The U-shaped locking flange 59 is disposed upon the inner face of the panel 60, and therefore concealed in assembly. This form of the invention requires no separate fastening elements for detachably connecting adjacent cornice sections together in assembly. All other parts are identical with corresponding parts shown and described in connection with the first form of the invention.

It is to be understood that the forms of the invention herewith shown and described are to be taken as preferred examples of the same, and that various changes in shape, size and arrangement of parts may be resorted to without departing from the spirit of the invention or the scope of the subjoined claims.

Having thus described my invention, I claim:

1. An ornamental curtain support for a window frame comprising a substantially horizontal curtain rod secured to the window frame and spaced laterally forwardly of the window frame, a cornice arranged adjacent to the curtain rod and extending above and below the rod and throughout its entire length and substantially completely concealing the curtain rod from view, the cornice including a plurality of separate detachably connected sections, spaced hanger brackets secured to the inner faces of the cornice sections and engaging over the top of the curtain rod for suspending the cornice therefrom, stop lugs secured to the inner faces of the cornice sections above the hanger brackets, and a removable horizontal cover plate mounted upon the stop lugs and disposed above the curtain rod.

2. A window curtain cornice comprising sep-

arate front and corner cornice sections, the front cornice section including a substantially vertical panel, the corner cornice sections including front vertical panels arranged adjacent to the ends of the vertical panel of the front cornice section and side vertical panels, inturned registering apertured ears secured to the adjacent ends of the vertical panels of the front and corner cornice sections, bolt means detachably connecting the inturned apertured ears of the front and corner cornice sections, and hanger means secured to the inner faces of the front and corner cornice sections for detachably securing the cornice to a curtain rod.

3. A window curtain cornice comprising a plurality of separate cornice sections including vertical panels having laterally spaced free edges, and a separate removable locking slide engaging the free edges of each adjacent pair of vertical panels for detachably securing the cornice sections together in assembly.

4. A window curtain cornice comprising a plurality of separate detachable cornice sections including substantially flat vertical panels which overlap, and frictionally interfitting substantially U-shaped vertical locking flanges integrally secured to adjacent ends of said overlapping vertical panels for frictionally detachably securing the cornice sections together in assembly.

5. An ornamental curtain support for a window frame comprising a substantially horizontal curtain rod secured to the window frame and spaced laterally forwardly of the window frame, a cornice arranged adjacent to the curtain rod and extending above and below the rod and throughout its entire length and substantially completely concealing the curtain rod from view, spaced hanger brackets secured to the inner face of said cornice engaging over the top of the curtain rod for suspending the cornice therefrom, stop lugs secured to the inner face of the cornice above the hanger brackets, and a removable horizontal cover plate mounted upon the stop lugs and disposed above the curtain rod.

COSIMO D. BRUNO.
